Application filed September 2, 1932. Serial No. 44,741. Term of patent 3½ years.

To all whom it may concern:

Figure 1 is a side elevation of the pitcher. Figure 2 is a detail horizontal section through a portion of the pitcher.

The pitcher is preferably made of glass and is transparent. It is provided with vertically extending optic lines, due to variations in the wall thickness but is externally of generally circular horizontal cross-section.

I claim:

The ornamental design for a pitcher, as shown and described.
